UNITED STATES PATENT OFFICE.

ROBERT D. GREGG, OF KANKAKEE, ILLINOIS, ASSIGNOR OF ONE-HALF TO FRANK L. SHIDLER, OF KANKAKEE, ILLINOIS.

EXPANSION STRIP FOR CONCRETE ROADWAYS.

Application filed April 21, 1927, Serial No. 185,504. Renewed February 9, 1929.

This invention relates to that type of parting strips or plates used in the formation of sectional concrete roadways, pavements, etc., in which the strip or plates remain in 5 the completed roadway or the like to constitute an expansion joint for the same. And the present improvement has for its object:—

To provide a structural of a flat parting strip or plate, preferably composed of a fiber 10 and asphalt combination, generally known as tar board, adapted to provide an effective bonding of the strip or plate with the mass of roadway concrete, and which at the same time admits of a ready removal of the usual 15 bracing board by which the parting strip or plate is held in position, without any disturbance in the relation of the strip or plate to the mass of unset roadway concrete that is held in form by the strip or plate 20 and without damage to the upper corner or edge of said unset concrete mass, all as will hereinafter more fully appear.

In the accompanying drawing:

Fig. 1, is a detail vertical section, illustrating the ordinary manner and means for 25 positioning the parting strip in the formation of a sectional concrete roadway or the like, the strip embodying the features of this invention.

Fig. 2 is a detail elevation of the face of 30 the parting strip remote from the concrete receiving cavity of which the strip forms one wall.

Fig. 3, is a similar view of the face of 35 strip within said receiving cavity.

Fig. 4, is a detail longitudinal section of 40 the strip, on line 4—4 Fig. 2.

Fig. 5, is a detail elevation of a modified 45 form of the face of the strip shown in Fig. 2.

Like reference numerals indicate like parts 50 in the different views.

The parting or expansion strips now in 55 general use in the making of concrete roadways are known to the trade as "tar boards" which are formed of a body of fibrous ma-

terial saturated with tar, asphalt, or like 60 bonding and preservation material of an elastic nature. The present improvement, in connection with such type of parting and

expansion strips, involves a special forma- 65 tion of the respective faces of a strip of such nature affording a firm anchorage or connection of the side of the strip which forms one wall or face of the concrete receiv- 70 ing cavity, with the mass of roadway con-

crete in said cavity, and by means of which the bracing board by which the parting and expansion strip is held in proper place, can be readily removed after the filling and partial setting of the concrete material in said 60 cavity, without displacement of the strip or injury to the adjacent upper edge of such concrete mass. The attainment of such results are effected in the present improvement by a detail formation of a "tar board" 65 strip in manner as follows:

One side or face of the tar board strip 1, is formed with a series of depressions 2, preferably arranged in longitudinal rows, with such side or face adapted to form a wall 70 of the receiving cavity of a mass of roadway concrete, and into which depressions 2 the plastic concrete roadway mass is adapted to enter and provide a connection of parts 75 adapted to prevent relative independent vertical movement between the surfaces in contact. In connection with such formation of the strip 1, a material part of this invention consists in forming the opposite face or side of the tar board strip 1 with a series 80 of transverse depressions 3, in angular relation to the aforesaid depressions 2, preferably in right-angle relation, the purpose being to reduce frictional or adhesive contact between said face of the parting strip and 85 the bracing board or plank 4 by which the parting strip is held in proper position to constitute one wall of the receiving cavity in which the roadway forming mass of concrete 5 is placed and molded. The bracing 90 board 4 is held in place by the usual anchor stakes 6, or other usual means, as illustrated in Fig. 1.

With the above described formation and arrangement of parts, and after the concrete 95 mass 5 has partly set, the bracing board 4, can be readily removed without liability to disturbance of the parting strip in its proper relation to the mass of concrete and without danger of injury to the upper edge or corner 100 of such concrete mass.

Having thus fully described my invention, what I claim and desire to secure by Letters Patent, is:—

1. A tar board expansion strip for con- 105 crete roadways formed with a series of de- pressions in the face which forms a wall of the receiving cavity for a mass of roadway concrete and with a series of transverse de- pressions at right angle relation to the afore- 110

said depressions and in its other face, adapted to reduce the extent of adhesive contact with a bracing board used to hold the parting strip in position in the formation of the 5 roadway.

2. A tar board expansion strip for concrete roadways, formed with rows of longitudinally extending depressions in the face which forms a wall of the receiving cavity 10 for a mass of roadway concrete, and with a series of transverse depressions at right angle relation to the aforesaid depressions and in its other face, adapted to reduce the extent of adhesive contact with a bracing 15 board used to hold the parting strip in position in the formation of the roadway.

3. A tar board expansion strip for concrete roadways having a series of depressions

in the face which forms a wall of the receiving cavity for a mass of roadway concrete, said depressions extending approximately lengthwise of the strip, and in its opposite face with a series of depressions extending approximately transverse of the strip, the first mentioned formation providing effective retardance against independent upward movement of the expansion strip in relation to the concrete roadway mass, while the last mentioned formation provides for an easy upward removal of the ordinary bracing board, without disturbance of the proper relation of the expansion strip and the partly hardened roadway mass.

Signed at Chicago, Illinois, this 16th day of April, 1927.

ROBERT D. GREGG.
